(57) **CLAIM**

The ornamental design for a pair of hearing aids as shown and described.

DESCRIPTION

FIG. 1 is a front, right and top perspective view of a pair of hearing aids, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the pair of hearing aids that form no part of the claimed design. The article shown is the design for a right hearing aid. The design also includes the article for the left hearing aid which is not shown but is a mirror image of the article shown.
